UNITED STATES PATENT OFFICE.

HOWARD L. PAGE, OF CHICAGO, ILLINOIS, ASSIGNOR TO HOME STOVE & FOUNDRY COMPANY, A CORPORATION OF ILLINOIS.

CONCEALED LATCH FOR OVEN DOORS.

Application filed November 20, 1922. Serial No. 602,038.

To all whom it may concern:

Be it known that I, HOWARD L. PAGE, a citizen of the United States, residing at Chicago, county of Cook, State of Illinois, 5 have invented a certain new and useful Improvement in Concealed Latches for Oven Doors, and declare the following to be a full, clear, and exact description of the same, such as will enable others skilled in the art 10 to which it pertains to make and use the same, reference being had to the accompanying drawing, which forms a part of this specification.

The oven doors of gas stoves are provided 15 with catches for holding them yieldingly closed and permitting them to be opened by simply pulling sharply on the doors. The most usual form of catch is one which projects outwardly from the front wall of the 20 oven at the top of the door-opening and snaps over a projection on the upper edge of the door when the door is swung into its closed position. This type of catch not only 25 produces an undesirable projection on the front of the oven but, because of its nature, soon becomes more or less rusty, and thus mars the appearance of the front of the oven which, together with the door, may have an attractive enamelled or nickelized surface. 30 Furthermore, such catches must be made comparatively stiff, and therefore a strong push or pull is often required to move the door into or out of its closed position.

The object of the present invention is to 35 produce a simple and novel catch construction for an oven door which will leave the front surface of the oven and door uninterrupted by a projection of any kind, which will be completely concealed when the door 40 is closed, and which will efficiently perform its holding function without requiring the expenditure of any considerable force in order to close or open the door.

The various features of novelty whereby 45 my invention is characterized will herein-after be pointed out with particularity in the claims; but for a full understanding of my invention and of its objects and advantages, reference may be had to the following 50 detailed description taken in connection with the accompanying drawing, wherein:

Figure 1 is a front view of the oven side of a gas stove equipped with door catches embodying my invention;

55 Fig. 2 is a view, on an enlarged scale, of a

fragment of one of the door frames and doors, viewed from within the oven and showing the catch; and

Fig. 3 is a section taken approximately 60 on line 3—3 of Fig. 2.

In the drawing I have illustrated two doors, one above the other, but since the same catch device may be used on each, I shall confine the description to the catch as applied to one of the doors. 65

Referring to the drawing, 1 represents the door frame surrounding the door-opening 2 of an oven, the frame having an inwardly-directed flange 3 on the inner or rear side; this flange lying wholly within the oven and forming in rear of the door-opening a frame somewhat smaller than said opening. 4 is a door hinged at the bottom in a usual or suitable way, as indicated at 5, so as to permit the door to be swung from an open position into a closed position within the door-opening, with its outer surface substantially flush with the outer surface of the frame and bearing on the inner side against the shoulder formed on or by the flange 3. That portion of the flange which extends along the top of the door-opening is provided at the middle thereof with a hole 6 extending through the same. A dog or catch member 75 in the form of a flat plate 7 flanged along the upper edge as at 8, to form a head, extends vertically through the hole in the flange. Since the vertical depth or thickness of the flange is comparatively small I prefer to employ a holding plate 9 fastened 80 to the inner side of the frame across the catch or dog member so as to form a guide therefor. A leaf spring 10 extends across the upper end of the dog or catch underneath a rib or projection 11 on the frame and into a suitable anchoring device 12, so that the dog or catch tends constantly to position itself with its lower end projecting into the door-opening. The lower end of the 85 dog or catch is reduced to a knife edge, as indicated at 14, while the door is provided in the upper edge with a shallow V-shaped groove 15, so positioned that when the door is swung shut the dog will ride across the upper edge of the door until it drops into the groove. By making the groove shallow the dog will ride up out of the same easily 90 when a slight pull is applied to the door to open the same.

100 It will be seen that the catch is wholly 105 110

110

invisible from the outside of the oven when the door is closed, so that it does not mar the appearance of the oven and no pains need be taken to construct it of a material which will not rust or discolor. Furthermore, since the movement of the catch is in the plane of the door when the latter is closed and the controlling spring is effectively applied thereto, the locking action of 10 the catch will remain unimpaired for an indefinite length of time without making the groove in the door so deep as to require the application of a considerable force to open the door.

15 While I have illustrated and described with particularity only a single preferred form of my invention, I do not desire to be limited to the exact structural details thus illustrated and described; but intend to 20 cover all forms and arrangements which come within the terms employed in the definitions of my invention constituting the appended claims.

I claim:

25 1. The combination with an oven having a door opening and a frame-like flange sur-

rounding the opening and lying within the oven, of a door hinged so as to be movable into and out of the opening, a spring-actuated catch lying behind the door and extending through said flange, said door having in one edge a shallow groove adapted to receive the catch when the door is closed and thus hold the door closed without exposing any holding means on the exterior of the 35 oven.

2. The combination with an oven having a door opening and a frame-like flange surrounding the opening and lying within the oven, of a door hinged to the oven so as to 40 be movable into said door opening, said flange having a hole extending through the same, a dog slideable in said hole, a spring tending to hold said dog in a position in which it projects into said door opening, and said door having in the edge thereof a shallow groove adapted to receive the end of the dog when the door is closed.

In testimony whereof I sign this specification.

HOWARD L. PAGE.
